UNITED STATES PATENT OFFICE.

WILLIAM ZAISER, OF ROCKVILLE CENTER, NEW YORK.

DESIGN FOR A GRAND-PIANO LEG.

Application filed December 23, 1926. Serial No. 20,133. Term of patent 14 years.

To all whom it may concern:

Be it known that I, WILLIAM ZAISER, a citizen of the United States, and a resident of Rockville Center, Nassau County, New York, have invented a new, original, and ornamental Design for Grand-Piano Legs, of which the following is a specification, reference being had to the accompanying drawing, forming part thereof.

The figure is a perspective view of a grand piano leg showing my new design.

I claim:

The ornamental design for a grand piano leg substantially as shown.

In testimony whereof I have hereunto signed this specification.

WILLIAM ZAISER.
